PICK OR PLECTRUM

Hollis W. Wolcott, Mount Vernon, Ohio

Application April 7, 1938, Serial No. 200,783

3 Claims. (Cl. 84—322)

This invention relates to a pick or plectrum to be used for setting or imparting motion to the strings of certain musical instruments and by way of example, of the guitar.

5 It is particularly aimed to provide such a pick as will practically eliminate noise now occasioned by contact of the usual pick with the strings, and more particularly to provide a pick with the use of which, the tone and quality of the music will 10 be enhanced, and in which the picking may be effected more rapidly and efficiently, and in which the pick does not require breaking in and is less subject to fracture or damage.

A very important object of the invention is to 15 provide a pick of rubber or rubber composition which is flexible and yieldable although relatively stiff.

The more specific objects and advantages will 20 become apparent from a consideration of the description following taken in connection with the accompanying drawing illustrating an operative embodiment.

In said drawing:—

Figure 1 is a view in elevation of one form of 25 pick constructed in accordance with the invention;

Figure 2 is a vertical sectional view taken on the line 2—2 of Figure 1;

Figure 3 is a cross sectional view taken on the 30 line 3—3 of Figure 1;

Figure 4 is a front elevation of a modified form 35 of pick;

Figure 5 is a section taken on the line 5—5 of Figure 4;

Figure 6 is a section taken on the line 6—6 of 40 Figure 4;

Figure 7 is a front elevation of another form 45 of pick; and

Figure 8 is a section taken on the line 8—8 of 50 Figure 7.

Referring specifically to the drawing, wherein like reference characters designate like or similar parts, one embodiment of the pick is disclosed in Figures 1, 2 and 3, being designated 10 as a whole 45 and generally triangular in shape so as to provide three points or corners, all of which are preferably rounded. One edge of such pick 10 may be blunt if desired as at 11 while the pick is chamfered or reduced toward its other edges as at 12, if desired.

The said pick is made of a resilient or yieldable material, usually rubber or a rubber composition and the exterior or string engaging surface of the pick is yieldable or elastic, although the pick is relatively stiff.

Various modifications may be resorted to, for instance the form of Figures 4, 5 and 6 being employed, this form being of the same material as Figure 1 and substantially triangular so as to

have three points. This pick or body generally designated 10a, is chamfered from the center to all of the edges and to facilitate gripping and manipulation preferably has central depressions at 13, extending inwardly from opposite sides or 5 faces.

Still another modification as in Figures 7 and 8 is suggested, the same being of like material as the other forms. This pick or body is generally designated 10b, having for instance a single picking point or portion as at 14, the pick being generally round and enlarged to provide said portion 14. The upper edge portion of the pick 10b may be relatively blunt or rounded as at 15 and chamfered toward the point or portion 14. In opposite 15 surfaces, depressions 13a, like those at 13, may be provided.

Such a pick as is afforded by the various forms, is highly advantageous when made of the relatively stiff though elastic rubber, since a hard 20 surface will not contact the strings of the musical instrument, and the contact of the pick with the strings will be practically noiseless, thus enhancing the tone and quality and harmony of the resulting music. In addition, I find that picking of the strings may be effected more rapidly with 25 less danger of breakage in view of the toughness of the rubber or rubber composition, and may be used without a breaking in process, will wear longer and indefinitely and is generally more advantageous and efficient. 30

This pick or plectrum has an advantage over the picks now in use in that it has or offers added protection to the instrument used, in that it will not scratch or mar the surface of the instrument, 35 as do those in common use now.

Various changes may be resorted to provided they fall within the spirit and scope of the invention.

I claim as my invention:

1. A pick of the class described, having a body 40 of relatively stiff elastic material having a plurality of picking points, the body being chamfered toward all of said points.

2. A pick of the class described, having a body 45 of relatively stiff elastic material having a plurality of picking points, the body having a depression in one side thereof positioned to facilitate finger engagement and manipulation of either point, the body being chamfered toward all 50 of the points.

3. A pick of the class described, having a substantially triangular body of relatively stiff elastic rubber, the body having depressions in opposite sides thereof positioned for finger engagement to 55 facilitate manipulation of either point, the body being chamfered toward all of the points.

HOLLIS W. WOLCOTT.
